[57] CLAIM

The ornamental design for a point-of-sale merchandiser, as shown and described.

DESCRIPTION

FIG. 1 is a top, front and right side perspective view of the point-of-sale merchandiser of the present invention; FIG. 2 is a left side elevational view of the point-of-sale merchandiser of FIG. 1, the opposite side being the mirror image thereof;

FIG. 3 is a front elevational view of the point-of-sale merchandiser of FIG. 1;

FIG. 4 is a top plan view of the point-of-sale merchandiser of FIG. 1;

FIG. 5 is a bottom plan view of the point-of-sale merchandiser of FIG. 1; and

FIG. 6 is a rear elevational view of the point-of-sale merchandiser of FIG. 1.
